UNITED STATES PATENT OFFICE.

JULIUS MILLER AND DAVID MACOWSKY, OF SAN FRANCISCO, CALIFORNIA.

DESIGN FOR A CHILD'S ROMPERS.

57,367.

Specification for Design.

Patented Mar. 15, 1921.

Application filed May 7, 1919. Serial No. 295,492. Term of patent 3½ years.

To all whom it may concern:

Be it known that we, JULIUS MILLER and DAVID MACOWSKY, citizens of the United States, residing at the city and county of San Francisco and State of California, have invented a new, original, and ornamental Design for Children's Rompers, of which the following is a specification, reference being had to the accompanying drawings, forming part thereof.

Figure 1 is a view in front elevation of a child's romper showing our new design.

Fig. 2 is a view in rear elevation of the same.

We claim:

The ornamental design for a child's rompers as shown.

JULIUS MILLER.
DAVID MACOWSKY.
